UNITED STATES PATENT OFFICE.

WALTER J. RICHARDS, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN.

SUSPENSION DEVICE FOR FLUID-COMPRESSORS.

1,162,881.

Specification of Letters Patent.

Patented Dec. 7, 1915.

Application filed September 25, 1913. Serial No. 791,743.

To all whom it may concern:

Be it known that I, WALTER J. RICHARDS, a citizen of the United States, residing at Milwaukee, in the county of Milwaukee and 5 State of Wisconsin, have invented new and useful Improvements in Suspension Devices for Fluid-Compressors, of which the following is a specification.

This invention relates to devices for suspending 10 fluid compressors or other machines from the car body, and more particularly to a suspension device adapted for supporting motor driven compressors such as employed to supply fluid under pressure for operating 15 the brakes.

The compressor suspension heretofore commonly employed consists of a cage like structure made of heavy strap iron surrounding the compressor and braced in different 20 directions to give rigidity, particularly against jarring such as occurs at the time of starting and stopping the car, the tendency to jar being increased by the nature of the cage construction which must take 25 the thrust of the compressor at the lower side thereof where it rests on the cage straps. The cage construction also renders the compressor difficult of access and removal.

One object of my invention is to provide 30 an improved compressor suspension in which the suspending members are secured to and from a mechanical unit with the compressor, so that rigidity is secured with a suspension construction of minimum weight.

Another object of my invention is to provide 35 a compressor suspension which permits of the ready removal of the compressor and also easy access thereto when in position.

In the accompanying drawing, Figure 1 is 40 a side elevation, partly in section, of a compressor applied to a car body by means of my improved compressor suspension and Fig. 2 an end view thereof.

As shown in the drawing, the suspension 45 device preferably comprises three straps, two of which are secured to the compressor at the gear end and the third strap at the commutator end. The straps 1-1 at the gear 50 end are secured by bolts 2 to lugs 3 cast integral with the compressor body and the lower ends 4 of the straps are turned inwardly at right angles to the straps and the lugs 3 rest on the turned ends so as to relieve

the bolts 2 of the weight of the compressor. 55 The strap 5 at the commutator end of the compressor is preferably bent to conform to the contour of the end of the compressor and is secured to an integral lug 6 by bolts 7, the lower end 8 being turned at right angles 60 to provide a shelf for the lug 6 to rest on. The upper end 9 of the strap 5 is bent at right angles to the strap and the upper ends 10 of the straps 1-1 are similarly bent, so that the three ends face in the same direction. 65

A bracket 11 is secured by through bolts 12 to the car body 13 and is bent to form a centrally located recess 14 for the reception of the end 9 of strap 5. A second bracket 70 15 is secured to the car body 13 by bolts 16 and is provided with two recesses 17 for the ends 10 of the straps 1-1. The hanger straps 1-1 and 5 being secured to the compressor 75 18 form a mechanical unit with the compressor and the upper supporting ends of the straps being turned in the same direction, the compressor may be installed in position by merely slipping the supporting ends into the corresponding recesses in the 80 brackets 11 and 15. When in position, the hangers are secured to the brackets by means of bolts 19.

It will now be evident that my improved 85 compressor suspension provides rigidity with a minimum weight of material and that the compressor is easy of access and may be readily removed by merely withdrawing the bolts which secure the supporting hangers to the brackets. By employing three hanger 90 straps the supporting ends are always substantially in the same plane regardless of variations in the lengths of the straps, so that registry with the recesses in the brackets is assured. 95

Having now described my invention, what I claim as new and desire to secure by Letters Patent, is:—

1. The combination with a compressor casing provided with front and rear integral 100 lugs, of vertical hanger straps rigidly secured to said lugs and provided with horizontally turned ends, and supporting straps provided with recesses for the turned ends of the hanger straps, to thereby rigidly suspend the compressor casing from the car body. 105

2. The combination with a compressor

provided with integral lugs, of hanger straps secured to said lugs and having the lower ends bent to form supporting shelves for the lugs and the upper ends bent to face in the same direction and brackets secured to the car body and provided with recesses for receiving the upper ends of said hanger straps.

Copies of this patent may be obtained for five cents each, by addressing the "Commissioner of Patents, Washington, D. C."

In testimony whereof I have hereunto set my hand.

WALTER J. RICHARDS.
